STORM WINDOW STRUCTURE

William W. Schubert, Chicago, Ill.

Application February 20, 1940, Serial No. 319,928

1 Claim. (Cl. 20—55)

This invention relates to storm window structures for inside use, and the main object is to provide a metal combination storm window and screen assembly for inside installation and for winter and summer use. Another object is to provide a structure of the kind referred to in a simple, compact and efficient form, comprising a metal frame adapted to fit within the window frame, from which the inside stops, beading or strips have been removed and replaced by special strips for engaging a sponge rubber beading to contact the frame, the frame being divided into upper and lower sections by a parting strip, and a pair of specially constructed metal sash mounted in the frame with the panes thereof also rubber-sealed at their margins.

With the foregoing objects in view a preferred embodiment of the invention is shown in the accompanying drawings, wherein:

Figure 1 is an inside elevation of the assembly constituting the elements of the invention, as mounted within a conventional window frame.

Figure 2 is a cross-section on the line 2—2 of Figure 1.

Figure 3 is an enlarged sectional detail of the base parts of the assembly.

Figure 4 is an enlarged detail showing a method of anchoring the assembly within the window frame.

The frame and sash combination comprising the subject matter of the invention, is designed for application to a conventional window A having a frame B and including the inside facing strips C, from which the usual inner beading or stop-strips (not here shown) have been removed.

The invention comprises a special stop-frame 5 made of wood or metal strips and being on a cross-section of the form of an inverted L, with webs 5a and 5b defining a right-angled notch or groove 6. This frame is permanently mounted within the facing strips C of the window frame, in place of the removed stop strips. The frame 5 is constructed with the angular groove 6 facing inwardly, or towards the inner side of the window as shown, and channelled beading or lining 7 of soft rubber or the like, is seated along within the groove 6 all around the frame 5.

An inner metal storm frame 8 is then provided, adapted to fit within the facing strips C, at the inner side of the window frame. This frame includes side strips 8a, a top strip 8b, a bottom strip 8c and a medial cross strip 8d. All of the outer or marginal strips comprising the frame are angular or L shaped in cross-section and include webs 8e extended perpendicularly towards the groove 6 of the frame 5, the margins of these webs being rolled to form beads 8f for

forcing into the channels 7a of the rubber linings 7, thus providing tight joints all around the frame 8. The inner margins of the upper and lower openings of the frame 8, are rolled out towards the frame 5, as shown at 10 to form channels 10a for receiving rubber beads or sealing strips 11. The free margins or edges of the rolls 10 are turned back again towards the plane of the frame 8, that is to say towards the common plane of the strips or webs 9a, 9b, 9c, but fall so far short of this plane as to provide a slight space 18, permitting the insertion of glass panes 12 within the openings of the frame, in the plane of the strips 9a, 9b, 9c, with the panes having a bearing back against the sealing beads 11. The panes being thus mounted, metal facing strips 13 are mounted around the margins of the frame openings, the same overlapping the upper glass pane and being secured in place by means of short set-screws 14 passed through the strips into the webs of the frame 8. Thus an absolutely tight closure is provided at the inner side of the window, and the inclosed inner air space between the regular window and this storm window or assembly, provides effectual insulation against outer temperature changes.

If desired the lower pane of glass 12 may be set in a separate frame 15, and this frame then hinged at 16 to the main frame 8, whereby the hinged frame may be opened as desired for ventilation, or for summer use. Or for summer use a screen (not shown) may be substituted in the frame 15.

The frame 8 may be locked within the window frame by means of lugs 17 secured to the window frame.

From the foregoing description the construction and use of the invention will be readily understood, and while I have here shown and described certain structural features of the invention, the same may be changed or modified within the scope of the claim.

I claim:

In a structure of the kind described, a removable storm-frame for fixed positioning inside a window-frame inwardly of a stop-frame, the rails of the storm-frame being right-angled in cross section, with one web of each rail having a free edge directed centrally in the plane of the window and lying in a common plane and the margins thereof rolled openly and semi-circularly to receive a sealing bead, and with the margins of the other outwardly directed web of each rail rolled for contact with an outwardly mounted stop-frame.

WILLIAM W. SCHUBERT.
